(57) **CLAIM**

The ornamental design for a children's activity walker, substantially as shown and described.

DESCRIPTION

FIG. 1 is a perspective view of a children's activity walker according to another aspect of the design.

FIG. 2 is another perspective view of the children's activity walker of FIG. 1.

FIG. 3 is a rear view of the children's activity walker of FIG. 1.

FIG. 4 is a front view of the children's activity walker of FIG. 1.

FIG. 5 is a side view of the children's activity walker of FIG. 1, the opposite side being substantially a mirror image thereof.

FIG. 6 is a top view of the children's activity walker of FIG. 1; and,

FIG. 7 is a bottom view of the children's activity walker of FIG. 1.

The broken line portions of the drawing figures are included to show portions of the article or environment that are not part of the claimed design.

1 Claim, 6 Drawing Sheets
